UNITED STATES PATENT OFFICE

JAMES F. SCHNABEL, OF CLEVELAND, OHIO, ASSIGNOR TO THE CLARK CONTROLLER COMPANY, OF CLEVELAND, OHIO, A CORPORATION OF OHIO

CONTROL SYSTEM FOR ELECTRIC MOTORS

Application filed March 3, 1928. Serial No. 91,929.

The present invention relates to systems for the control of hoists of cranes or other hoisting mechanism and particularly provides for controlling mechanism for providing smooth and accurate control of the hoisting motor during both the hoisting and the lowering periods and under the widely varying load conditions usually met with on cranes.

10 The present controller also provides a safety dynamic circuit at the off position of the controller which circuit will prevent the load from descending rapidly in case of failure of the holding brake.

15 Another object is the provision in the controller of means for governing the speed of the motor during lowering so that the operator can accurately lower short distances slowly or can lower through longer distances 20 at as high a speed as is permitted by the general design of the hoist and at the same time, the operator is enabled to control the lowering of an empty hook where power must be applied to the motor from the source of 25 supply.

In particular the present controller is designed to accomplish the above results with fewer parts than previous types of controllers and to improve the operation especially in 30 lowering by making it possible to obtain much slower speeds on the first few contact points when lowering heavy loads and at the same time providing higher speeds when lowering the empty hook on the last points of the controller and also to provide means for adjusting the controller to meet the requirements of individual motors, brakes and particular 35 operating conditions. To the accomplishment of the foregoing and related ends, said 40 invention, then, consists of the means hereinafter fully described and particularly pointed out in the claims.

The annexed drawings and the following description set forth in detail certain mechanism embodying the invention, such disclosed means constituting, however, but one of various mechanical forms in which the principle 45 of the invention may be used.

In said annexed drawings:—

50 Fig. 1 is a diagrammatic layout of the

controller contacts and showing the resistors and the connections between resistors and the contacts; Fig. 2 is a diagrammatic view of the controller arm showing the cross contacts employed and diagrammatically showing the off position of said controller; Fig. 3 is a wiring diagram showing the controller in its hoisting position and showing in full lines the controller as arranged on the first contact points and in dotted lines the position on the last contact points; Fig. 4 is a wiring diagram showing the safety braking circuit at the off position of the controller; Fig. 5 is a wiring diagram showing the dynamic braking circuit of the controller in the 55 lowering position, the full lines indicating the first contact points and the dotted lines indicating the circuit at the last contact points during lowering; Fig. 6 is also a wiring diagram of the motor circuit in the lowering position to more clearly show the arrangement when the motor is driving down a light load; Fig. 7 is a view similar to Fig. 1 but showing modified arrangements of resistance banks and groups of contacts; Fig. 8 60 is a wiring diagram similar to Fig. 3 but showing the use of four banks of resistance; Fig. 8A is a view similar to Fig. 8 but showing a slightly modified wiring arrangement; and Fig. 9 is a wiring diagram similar to Fig. 5 but showing the four banks of resistances as in Fig. 8.

On the drawings, are conventionally shown a motor armature 1, a series field winding 2, a magnetic brake 3, the banks of resistors 4A, 5 and 6, and the controller arm 10 for varying the resistance and for controlling the various circuits which are to be obtained during the hoisting, holding and lowering of loads by the motor. In Figs. 1 to 6 are shown three 70 banks of resistors, with four groups of contacts 14, 14A, 15 and 16, the groups of contacts 14 and 14A both being connected to the resistance 4A, the group of contacts 15 to the resistance 5, and the group of contacts 16 to the resistance 6.

The controller arm 10 is best shown in Fig. 2 and consists of a hub 11 carrying two arms at substantially right angles to each other, these arms carrying contact fingers or brushes 100

which contact with the groups of contacts on the face plate of the controller and with the inner ring of contact plates and the dead plates between groups. One of the arms 44 is provided with two pairs of electrically connected fingers or brushes 24 and 24A and 25 and 25A, while the other arm 45 has merely a single finger or brush 26 and 27 at the ends; these two fingers being electrically connected by a suitable connector bar 48 or the like and the controller arm 10 is shown as provided with a conventional operating handle 18.

Referring to the drawings, it will be seen that in the hoisting position, the resistance bank 4A is the variable resistance which is placed in the line between the positive (+) terminal and the motor armature 1, the resistance 6 controlling the variable shunt circuit, and resistance 5 is used to insert variable resistance in the line between field coil and the negative (-) terminal.

In Fig. 3 which shows the circuit in its hoisting position, and on the first contact points as illustrated in full lines, the main circuit is through the positive (+) terminal, the positive line 30, positive center plate 12, contact brushes 24 and 24A of the controller arm to the first contact point of the group 14A, through the entire resistance bank 4A to the armature terminal A, the armature 1, the series field 2, the magnetic brake 3, to the brake terminal B, and the entire resistance bank 5 and the fingers or brushes 25 and 25A, to the negative center plate 13, blowout coil 17 and the negative line 31 to the negative (-) terminal. As the motor hoists the load and the controller handle is moved counter-clockwise, the contact finger 24 passes over the group 14A of contact points, thus cutting out successive resistors in the bank 4A in the circuit, while the contact finger 25 similarly passes over the group 15 of contact points gradually reducing the resistance 5, and at the same time the two contact fingers 26 and 27 on the other controller arm connect a variable shunt circuit around the armature.

This variable shunt circuit around the armature 1 is connected from terminal AF through resistance bank 6, contact group 16, brush 27 to brush 26, contact group 14 and the interconnected group 14A to the other side of the armature through the brushes 24 and 24A. The bank 6 is thus gradually introduced into the shunt circuit while the fingers 26 and 24 by their opposite movement in relation to bank 4A maintain the least possible amount of this resistance 4A in the shunt circuit at such time until the arms relatively pass each other on the inter-connected groups 14 and 14A after which the bank 4A will be rapidly added to the shunt circuit. Before the controller reaches the final full on hoisting position, the shunt circuit is completely removed by the contacts 26 and 27 reaching the unconnected

contact points 54 and 56 at the ends of the banks 14 and 16 respectively.

In order to more closely control the resistance in the shunt circuit, the inter-connections 74 may be of graduated resistance values or may have graduated resistances 84 inserted, such resistances and graduated values being illustrated at 84 in Figs. 3, 5 and 6. The use of such added resistance in the interconnections 74 will depend upon the value of the resistance 6 or upon the resistance of the separate resistor steps, and the hoisting and lowering characteristics of the entire hoisting mechanism to which the controller is applied.

The interconnections between the contacts of groups 14 and 14A may be varied as between the several contacts of each group to obtain the required amounts of resistance in the circuit at the various contact points as the controller handle is moved.

When the controller is at the off position, a safety braking circuit is obtained as best shown in Fig. 4 in which position a shunt circuit 48 with no resistors is closed about the motor armature and field, thus making the motor a generator if rotated in the lowering direction. This circuit is obtained through contact plates 60 and 61 on the controller and brushes 26 and 27 on the controller arm, the contact 60 having a connecting line 51 with the terminal FB and the plate 61 a connecting line 52 with the terminal A of the armature, thus closing the internal circuit including the armature and field but not including the magnetic brake.

In Fig. 5 the lowering circuit is shown as considered with an overhauling load, the two contact brushes 26 and 27 of the arm 45 having been moved to the end contacts of groups 14A and 15. After the brushes 26 and 27 have passed over certain contacts of groups 14A and 15, the fingers 25 and 25A having passed over the unconnected contacts connect the resistance 6 in series with the positive (+) terminal through center plate 12 and line 30, thus providing a starting current sufficient to release the magnetic brake and to start the lowering action as the fingers 24 and 24A having passed over the unconnected contacts, complete the parallel circuits through contact group 14, plate 13, blowout coil 17, the negative line 31, to the negative (-) terminal. Thus in lowering, the circuit is changed to make a shunt motor or generator and as the controller is moved, the closed motor circuit, or dynamic braking circuit under an overhauling load, has the resistance 5 gradually added and the bank 4A is likewise gradually added into this closed motor circuit by the movement of arm 45 and fingers 26 and 27. Thus resistance is increased rapidly in the closed motor circuit to obtain proper speed control of the overhauling load at all times.

In Fig. 6, the same motor circuit is illustrated as in Fig. 5 but arranged slightly differently to better illustrate the arrangement during lowering when the motor is used to drive down an empty hook or a load that is not heavy enough to overhaul. As in Fig. 5, the first power position shows the resistance 6 connected to the positive (+) terminal through line 30, positive plate 12 and fingers 25 and 25A, while the fingers 26 and 27 close the motor circuit through certain contact points of resistance group contacts 14A and 15 thus starting the motor as contacts 24 and 24A close the circuit to the negative (-) terminal through the other end contact of bank 4A, the negative plate 13, blow out coil 17 and line 31. Thus at the starting position, the circuit provides a shunt motor with resistance 6 in series with the line and part of resistance 4A also in series with the line but with a closed circuit around the armature 1, field 2, and brake 3 so that the motor can act as a dynamic brake if the load starts to overhaul. To maintain the armature circuit and the field circuit in the desired resistance ratios, it will be noticed that as the resistance 5 is added into the parallel field circuit, the resistance 6 is being removed from the line circuit and also some of the resistance 4A while a portion of the resistance 4A is also added to the armature circuit. As the fingers 27 and 24 relatively pass each other on the resistance bank 4A, the circuit rapidly changes its characteristics, the resistance in the armature circuit from the positive line through the armature to the negative line being rapidly reduced as both resistance 6 and resistance 4A are cut out of the circuit while the resistance in the field circuit is increased as resistance 5 and resistance 4A are being added although resistance 6 is being removed. Thus at the full lowering position of the controller, the armature is substantially across the line, while the field has resistances 4A and 5 both in series with it across the line. In this manner the field which is of low resistance due to its normal use as a series field is always provided with sufficient additional resistance to be used satisfactorily as a shunt field during the lowering operation.

In Figs. 7 and 8, a modified wiring diagram is shown, similar to Figs. 1 and 3, but showing a fourth bank of resistors 4 instead of using the two groups of contacts 14 and 14A connected to the same resistance bank 4A. Thus the controller arm contact finger 26 contacts group 14 and cuts bank 4 into the variable shunt circuit while the controller finger 24 operating over group 14A cuts the bank 4A into the motor circuit. Instead of using the one bank 4A for both the motor circuit and the shunt circuit and controlling this bank in the two circuits from both con-

tact groups 14 and 14A, the shunt circuit is separately controlled from the bank 4 by the contact 26 on the controller arm and the bank 4A in the motor circuit by the contact 24 on the controller arm. The same type control is obtained for the lowering circuit, the contact finger 27 passing over the group 14A and thus controlling the bank 4A while the bank 4 is controlled by finger 24 passing over group 14. Three banks of resistors with the double control for one bank is found satisfactory for some types of installations but the four banks are preferred for many types on account of the adjustable features secured in this arrangement.

Furthermore the four bank type of controller with an adjustable tap 75 provides better operation for both the hoisting and lowering circuits and allows the proper amount of resistance to be maintained in the motor armature circuit during the entire controller range for lowering. This forces sufficient current through the field circuit to release even a very sluggish acting magnetic brake. By the use of the adjustable tap connection 75 between the end contact of one bank 4 and the other bank 4A, there is always left a predetermined fixed amount of resistance in the armature circuit and this amount can readily be adjusted to meet the actual conditions of the hoisting mechanism and motor. The adjustable tap 75 also makes it possible to change and control the field strength and thus adjust and vary the final speed of both hoisting and lowering to meet the actual operating conditions but at the same time does not change the use of the entire banks of resistors 4A and 5 in the internal or dynamic braking circuit. This adjustable tap arrangement is best shown in Figs. 8 and 9, the bank 4 of resistance which is in the variable shunt circuit being connected not directly to the armature line but to one of the taps of the resistance bank 4A and this connection 75 being adjusted to fit the particular motor and field operating conditions. The same adjustment is shown in Fig. 9 for the lowering circuit.

In Fig. 8A is shown a modified way of accomplishing the same result. In this case while only three banks of resistances are employed as in the first form, the fourth group of contacts is not interconnected but are connected together by short leads 39, also shown in dotted lines on Fig. 7, thus substantially short circuiting all of these contacts. Where such constructions is employed the resistance of the banks is preferably of sufficient value to equal the combined resistances of banks 4 and 6 both in the armature shunt circuit and the lowering circuit, the adjustable tap 75 allowing the same fine adjustment for speed and motor control as before as the bank 4A is used in the same manner as in Figs. 8 and 9.

Briefly the operations of the device is as

follows: To hoist a load, the controller arm is moved from the off position as indicated in Fig. 2, in a counter-clockwise direction thus closing the armature shunt circuit by the connected contacts 26 and 27 on arm 45 through contact groups 14 and 16 and the motor circuit through the pairs of contacts 24, 24A and 25, 25A through contact groups 14A and 15 and center contact plates 12 and 13. As the arm is moved the shunt circuit resistance increases by adding resistors of bank 6 and finally by rapidly adding bank 4 as shown in Figs. 1 and 3 or by gradually adding both banks as in the form shown in Figs. 7 and 8 and this circuit breaks or is opened when the fingers 26 and 27 reach the dead contacts 54 and 56 which takes place before the motor circuit fingers 24 and 25 reach the end contacts of banks 14A and 15. In the off position of the controller, the arm contacts 24, 24A, 25 and 25A rest on the dead plates 33 and 34 and the only closed circuit is the safety dynamic braking circuit closed by the connected fingers 26 and 27, the plates 60 and 61 around the armature 1, and field 2 through the terminals A and FB but not including the magnetic brake 3. In the lowering position, the controller arm is moved clockwise and thus the braking circuit is first moved to the end contacts of banks 14A and 15 through the contact brushes 26 and 27, thus including the magnetic brake in this circuit so that current flow will release the same. The bank 6 of resistance is added into the circuit between the positive (+) terminal and the motor and the bank 4 is connected between the motor circuit and the negative (-) terminal. These same circuits are obtained whether three banks of resistors and four groups of contacts are employed or four banks of both resistors and four groups of contacts are employed, as will be clear from Figs. 3 to 9 inclusive.

In the present controller, four groups of contacts are employed and are controlled by four contact brushes on the crossed controller arm, and thus three or four banks of resistors may be employed at all times, from the one face plate and set of arms. Not only does the use of the crossed controller arm allow the three or four banks of resistors as shown in the present form to be employed but it also permits these banks to be used in the most desirable manner. In hoisting the load it is desirable to have the individual resistors of different resistance values with the highest resistance at the first contact and the values gradually reducing to the last contact point. In lowering, particularly in the dynamic braking circuit, it is desirable to introduce the resistances into the circuit in the opposite way, the steps of low resistance value being first introduced and the steps of high resistance value being introduced last. Thus in the present controller, the same pair of banks

of resistors and groups of contact points are employed to introduce resistance into the circuit for both hoisting and lowering but in one case the arms and fingers move over the contacts in one direction and in the other case in the opposite direction. The same desirable arrangement is obtained from the third bank which is used as the resistance in the variable resistance armature shunt circuit in hoisting in which use it is desirable to add resistances of constantly increasing value. This bank is also used in lowering as the resistance in the line between the positive line and the parallel circuits and is gradually reduced, the first steps being those of highest resistance and gradually decreasing in resistance value.

All these features are obtained from the single face plate and one set of crossed arms and the same sets of contacts are in constant use at all times. The two sets of contacts for one bank may be in use at the same time and this double use of one bank makes it possible to obtain the desired type of resistance changes in the circuit both in hoisting and lowering from a single face plate type controller without the use of extra contact rings and outside special equipment. Where four banks are employed, or the short circuited contacts, the adjustable tap construction allows the controller to be closely adjusted to meet particular motor requirements or operating conditions as to hoisting and lowering speeds.

In addition to the features just set forth, the present controller is of particular advantage both to the manufacturer and to the user because the contacts and dead plates on the face of the controller, the details of the blow out coil, contact brushes and holders are all substantially the same as those on controllers for other motions which would be used on the same crane, such as the controllers for the bridge and trolley and sometimes other auxiliary motions. Heretofore, it has ordinarily been necessary to have special types of contact plates and rings on the controller for the hoisting operation which includes a dynamic braking circuit but due to the cross contact arms used in the present controller, it has been found possible to adapt the standard type of reversing controller plates to the present type of controller and thus manufacturing costs are reduced and operating costs are likewise reduced as only one set of spare parts are necessary for several controllers.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a motor control system for hoists and the like, the combination of a motor, having an armature, a field and a magnetic brake, and a controller adapted, during lowering, to connect said armature and a variable resistance in a power circuit and to connect the field and brake with a second variable resistance in a parallel power circuit, said controller being also adapted to simultaneously close a dynamic braking circuit around said armature, said field and said brake through said two resistances, and said controller being adapted to open the power circuit while a portion of said two resistances are maintained in said braking circuit and then gradually removing said two resistances from said braking circuit. 5
2. In a motor control system for hoists and the like, the combination of a motor, having an armature, a field and a magnetic brake, and a controller adapted, during lowering, to connect said armature and a variable resistance in a power circuit and to connect the field and brake with a second variable resistance in a parallel power circuit, said controller being also adapted to simultaneously close a dynamic braking circuit around said armature, said field and said brake through said two resistances, said controller being adapted to open the power circuit while a portion of said two resistances are maintained in said braking circuit, and being finally adapted to maintain said dynamic braking circuit around said arm and field with no resistance therein. 10
3. In a control for hoisting motors, the combination of the motor armature and field connected in parallel circuits for lowering, and providing a dynamic braking circuit, a bank of resistance having one end connected in series with the armature circuit, an adjustable tap connection between one line terminal and a point on said bank of resistance to leave a predetermined amount of said bank in circuit with said armature at full on lowering position and means for adjustably connecting said field circuit to said bank during lowering to obtain varying lowering speeds. 15
4. In a control system for hoisting motors, the combination of a motor armature and a field and magnetic brake connected for lowering in parallel circuits, and a controller providing a bank of resistance having one end connected to the armature circuit, a second bank of resistance having one end connected to the field and brake circuit, means for adjustably connecting varying amounts of said two banks in a dynamic braking circuit, and an adjustable tap connection between said first bank and one of the line terminals, to obtain an adjustable predetermined amount of resistance in the field circuit at the full on lowering position. 20
5. In a control system for hoisting motors, the combination of a motor armature and a field and magnetic brake connected for lowering in parallel circuits, a controller having four groups of contacts and four banks of resistance connected thereto, a controller arm adapted to simultaneously control all of said banks by movement over said groups, one of said banks having one end connected to the armature circuit, the second bank having one end connected to the field and brake circuit, the third bank being connected between one line terminal and the parallel circuits, and the fourth bank having one end adapted for adjustable connection with said first bank and adapted for varying connection by said controller arm with the other line terminal, two of the controller arm brushes for two groups being adapted to close a dynamic braking circuit through said first and second banks, said adjustable tap connection being adapted to provide an adjustable predetermined resistance in the field circuit and a different amount of resistance in the armature circuit at full on lowering position to obtain the desired full on lowering speed. 25
